CLAIM

The ornamental design for a urine specimen collection unit, as shown and described.

DESCRIPTION

FIG. 1 is an isometric view of a urine specimen collection unit showing my new design in use on a toilet;

FIG. 2 is an isometric view thereof;

FIG. 3 is a front elevational view thereof;

FIG. 4 is a rear elevational view thereof;

FIG. 5 is a left side elevational view thereof;

FIG. 6 is a right elevational view thereof;

FIG. 7 is a top plan view thereof; and,

FIG. 8 is a bottom plan view thereof.

The broken lines showing the toilet are for illustration purposes only and form no part of the claimed design.

1 Claim, 4 Drawing Sheets
